TANK FURNACE HEATING MEANS

Filed Jan. 29, 1927

Inventor
Robert P. Callard

By *Frank Fraser*

Attorney

UNITED STATES PATENT OFFICE.

ROBERT P. CALLARD, OF CHARLESTON, WEST VIRGINIA, ASSIGNOR TO THE LIBBEY-
OWENS SHEET GLASS COMPANY, OF TOLEDO, OHIO, A CORPORATION OF OHIO.

TANK-FURNACE-HEATING MEANS.

Application filed January 29, 1927. Serial No. 164,459.

The present invention relates to a tank furnace, and more particularly to an improvement to the heating means therefor.

An important object of the invention is to provide in a tank furnace, including a checker-chamber and checker-bricks arranged within said chamber, means for positively insuring that a flow of air passing through the chamber will pass between the checker-bricks 10 arranged therein.

Another object of the invention is to provide in a tank furnace, including a checker-chamber and a plurality of checker-bricks arranged therein, a slab carried by the top of the 15 chamber wall and associated with the checker-bricks in a manner that a flow of air passing through the chamber will be forced to pass between the checker-bricks and in around the same.

Still another and important object of the invention is to provide in a tank furnace, including a checker-chamber and a plurality of checker-bricks adapted for alternate flows of hot and cold air to be passed therethrough, 25 means whereby both the heated and cold air will be caused to pass between the checker-bricks and not short circuited around a gap formed between the top of the checker-bricks and the checker-chamber top formed by reason of the expansion and contraction of the 30 bricks when subjected to the action of the air flows.

Other objects and advantages of the invention will become more apparent during the 35 course of the following description.

In the drawings wherein like numerals are employed to designate like parts throughout the same,

Fig. 1 is a diagrammatic plan view of a 40 form of tank furnace to which the present invention applies, and

Fig. 2 is a fragmentary vertical sectional view through one of the checker chambers and associated parts, illustrating my invention 45 in use.

The tank furnace illustrated is designed primarily for the production of molten glass from which articles can be formed, but it is to be understood that the invention is in no 50 way restricted to a glass tank furnace.

The numeral 5 designates a tank furnace in its entirety. The furnace is adapted to contain a mass of molten glass 6 or other material to be worked upon which may be intro-

duced by means of the doghouse 7. Arranged 55 on both sides of the furnace, as illustrated, is a plurality of regenerative heating means 8. As is well known in the art, the regenerative type of furnace is periodically changed from side to side, that is, for one period of the operation the flames will issue from one side of the furnace and the exhaust gases will pass through the opposite sides to the stack. To conserve heat, etc., the exhaust gases are passed through a checker-work which comprises a plurality of bricks piled up in a suitable manner to form an open brick-work adapted to absorb heat from the heated gases. Upon reversal of the operation, the side of the furnace that has been in operation is cut 70 off and the opposite side is adapted to produce the heating flames. The air that is used with the gas for the purposes of heating is pre-heated by passing it through the checker-brick arrangement above referred to. 75

Due to the contraction and expansion of the checker-bricks, they settle and leave a gap between the checker-brick and the top of the checker-chamber in which the brick is contained, and as the air naturally follows the path of least resistance, it short circuits around the top of the checker-brick pile so that the incoming cold air does not get the benefit of the heated checker-chamber, which results in a loss of efficiency. 85

The numeral 9 designates a gas pipe arranged near the port of the regenerator 8. The checker-chamber 10 is provided with the plurality of checker-bricks 11 arranged in a criss-cross fashion to provide openings 90 through which a flow of air may be passed. The incoming air is introduced through a tunnel 12 up through the opening 13 in the bottom of the checker chamber and preferably through the checker-bricks 11, and on into the channel 14. The numeral 15 designates a gap between the top of the checker-brick pile and the top 16 of the checker-chamber. As there is a certain amount of dust and other foreign matter conveyed by the exhaust gases, the checker bricks collect a certain amount of dirt which adds a slight resistance to the passage of the air therebetween. When the gap 15 has been formed, and in actual practice this gap sometimes 100 amounts to as much as six inches, the incoming air will have a tendency, due to less resistance, to pass around the top of the

checker-brick pile and on toward the port. Obviously, the air in passing around in this manner will not be efficiently preheated.

In accordance with the present invention, 5 a hanging key block 17 is provided, being supported by the top of the checker-chamber 16 and depending a sufficient distance into the checker-chamber to prevent a short circuiting of the cold air. A recess 18 can be formed 10 in the checker-brick pile to accommodate the hanging key block 17. It will be seen that, although the gap 15 is present, the key block 17 will prevent a short circuiting of the air causing the air to pass between the checker- 15 bricks, and thus become preheated.

In Fig. 2, the regenerator shown is in operation, the flame 19 being created by a mixture of the air passing in the path indicated by the numerals and mixing with the gas 9.

20 Upon reversal of the tank, the heated gases from the opposite side of the furnace will pass through the checker-bricks 11 and through the tunnel to the stack, thus heating the checker-bricks for the next reversal.

25 It is to be understood that the form of the invention herewith shown and described is to be taken as the preferred embodiment of the same, and that various changes in the shape, size and arrangement of parts may 30 be resorted to without departing from the spirit of the invention or the scope of the subjoined claims.

I claim:

1. A tank furnace including a checker- 35 chamber having an inlet at the bottom and an outlet at the top thereof arranged in staggered relation to said inlet, a checker construction composed of checker-bricks arranged within said chamber and spaced from 40 the side walls and top wall thereof, and means for preventing the free passage of the incoming air through the space above the checker construction and for directing the said air between the checker-bricks.

45 2. A tank furnace including a checker-chamber having an inlet at the bottom and an outlet at the top thereof arranged in staggered relation to said inlet, a checker con-

struction composed of checker-bricks arranged within said chamber and spaced from 50 the side walls and top wall thereof, and a baffle wall obstructing the space above the checker-bricks to direct the incoming air through the checker construction.

3. A tank furnace including a checker-chamber having an inlet at the bottom and an outlet at the top thereof arranged in staggered relation to said inlet, a checker construction composed of checker-bricks arranged within said chamber and spaced from 60 the side walls and top wall thereof, and a key block carried by the top wall of said chamber and depending downwardly into the checker construction for preventing the passage of the incoming air through the space 65 above the checker construction and for directing its course therethrough.

4. A tank furnace including a checker-chamber having an inlet at the bottom and an outlet at the top thereof arranged in staggered relation to said inlet, a checker construction composed of checker-bricks arranged within said chamber and spaced from 70 the side walls and top wall thereof, and means arranged above the checker construction for obstructing the passage thereabove to cause the incoming air to pass between the checker-bricks.

5. A tank furnace including a checker-chamber having an inlet at the bottom and an outlet at the top thereof arranged in staggered relation to said inlet, a checker construction composed of checker-bricks arranged within said chamber and spaced from 75 the side walls and top wall thereof, and a key block carried by the top wall of the checker-chamber and depending downwardly into a recess in the top of said checker construction for preventing passage of the incoming air over the top of the checker construction and for directing its course between the checker-bricks.

Signed at Charleston, in the county of Kanawha and State of West Virginia, this 25th day of January 1927.

ROBERT P. CALLARD.
